UNITED STATES PATENT OFFICE

2,517,949

RETORT TYPE LIQUID FUEL BURNER WITH
FLAME DEFLECTOR AND STARTING PAN

George W. Wargo, Live Oak, Fla.

Application February 27, 1947, Serial No. 731,302

2 Claims. (Cl. 158—70)

1

My invention relates to improvements in fuel oil burners for heating tobacco barns equipped with heat conducting and radiating flues.

The primary object of the invention is to provide a simply-constructed, inexpensive and efficient burner adapted for easy connection to such flues from outside a tobacco barn and which is economical to operate, does not require forced draft, and provides a hotter flame with a given size of burner and a lower rate of fuel consumption than other devices designed for similar purposes.

Other and subordinate objects, also comprehended by my invention, together with the precise nature of my improvements and the manifold advantages thereof, will be readily understood when the succeeding description and claims are read with reference to the drawings accompanying and forming part of this specification.

In said drawings:

Figure 1 is a view in horizontal section, partly in elevation, illustrating my improved burner in a preferred embodiment thereof connected to a flue system of a tobacco barn;

Figure 2 is a fragmentary view in vertical longitudinal section taken on the line 2—2 of Figure 1 and drawn to a larger scale;

Figure 3 is a view in transverse section taken on the line 3—3 of Figure 2 and drawn to a still larger scale;

Figure 4 is a view in horizontal section taken on the line 4—4 of Figure 3.

Referring to the drawings by numerals, my improved burner in the illustrated embodiment thereof comprises, as its basic element, a tubular casing 1 of any suitable length formed preferably of a section of pipe, and which is designed to be connected at a front end thereof, in any suitable manner, not shown, to the rear end of a branch nipple 2 extended horizontally out of one side of a tobacco barn 3 from a flue system 4 adapted to communicate with a smokestack, not shown. As will be understood, the casing 1 opens at its front end directly into the branch nipple 2. The particular type of flue system, other than as regards the nipple 2, is not important to the invention and therefore need not be entered into further. A rear end wall 5 closes the lower half of the rear end of the casing 1 and has hinged thereto, as at 6, a semicircular draft control door 7 vertically swingable into opening and closing positions relative to the upper half of the rear end of said casing. A ratchet-toothed bar 8 hinged, as at 9, on the casing 1 to swing

2

downwardly into an edge notch 10 in said door 7 provides for latching said door 7 in different open positions. The described casing 1 forms a combustion chamber 11 therein communicating at its front end with the flue system 4 by way of the nipple 2 and communicating with atmospheric air at its rear end by way of the draft control door 7.

10 A cylindrical, hollow, fuel pre-heating element 12, substantially smaller in diameter than the casing 1 and having closed ends 13 extends endwise in the casing diametrically thereof and in the rear position of said casing. A single, longitudinal row of discharge ports 14 is provided 15 in the rear of said pre-heating element 12 in the horizontal diameter thereof and which may be of any size suitable for a purpose presently apparent.

Surrounding the fuel pre-heating element 12 20 is a combination baffle and pan element 15, of the same length as said element 12, and comprising a hollow shell relatively larger in cross section than said element 12, the major portion 16 of which is cylindrical in cross section with a 25 longitudinally extending, rearwardly, projecting baffle 17 of right-angled cross section extending from end to end of said element 15 in the horizontal diameter of the same. The baffle 17, as will be seen, presents a concave side to the row 30 of ports 14. End bottom flanges 18 in said element 15, together with a bottom segment 19 of said element, form a bottom pan 20 in said element. The flanges 18 fit part way around the bottom of the fuel pre-heating element 11 and space said elements 12, 15 apart at the bottoms thereof. A spacing collar 21 between the tops of said elements 12 and 15 space the same apart at the tops thereof. The major portion 16 of said element 15 is concentric to the fuel pre-heating element 12. A pair of rear, air-inlet slots 22, 23 in the major portion 16 of said element 15 extend along the top and bottom of the baffle 17. A substantially wider front slot 24 in said major portion 16 extends longitudinally 40 thereof whereby the front of said element 15 is open from the segment 19 to substantially the top of said element.

45 A fuel-feed pipe line 25 extends downwardly through the top of the casing 1 and the top of said element 12, and is threaded, as at 26, into the top of said element 12. The fuel feed line 25 may be connected to any suitable source of liquid fuel supply, not shown, and have interposed therein the usual control valve, not shown.

50 A flanged collar 27 surrounds the fuel feed line

25 and is suitably fixed on top of the casing 1 with a set screw 28 therein turned against said line 25 so that said elements 12, 15 are suspended in the casing 1 by said line 25.

Referring now to the operation of the described burner. To start the burner, liquid fuel is fed into the fuel pre-heating element 12, by way of the fuel feed line 25, until the liquid fuel overflows out of the ports 14 into the pan 20. The overflow of liquid fuel in the pan 20 is ignited through either slot 22 or 23 to pre-heat the fuel pre-heating element 12. When said element 12 has been pre-heated to the proper temperature, the liquid fuel therein is converted into gas which issues in jet form out of the ports 14 against the concave side of the baffle 17 to rebound therefrom and spread around the fuel pre-heating element 12, such gas being ignited in a manner which will be clear and forming a hot flame completely surrounding the fuel pre-heating element 12 and issuing out of the front slot 24 into the combustion chamber 11. After the burner has been thus started, the flame will maintain the fuel pre-heating element 12 at a high temperature sufficient to convert liquid fuel continued to be fed therein into gas. Atmospheric air is drawn, by the chimney draft, into the casing 1 at the rear end thereof and through the combination baffle and pan element 15 which forms a mixing chamber for air and gas as will be clear. The draft may be regulated by means of the draft door 7.

The foregoing will, it is believed, suffice to impart a clear understanding of my invention without further explanation.

Manifestly, the invention, as described, is susceptible of modification, without departing from the inventive concept, and right is herein reserved to such modifications as fall within the scope of the appended claims.

What I claim is:

1. A burner for use with a tubular casing forming a combustion chamber, said burner comprising a cylindrical hollow fuel pre-heating element adapted to extend endwise in said casing diametrically thereof and provided with fuel discharger ports therein adapted to discharge toward the one end of said casing, a liquid fuel feed line to feed liquid fuel into said pre-heating

element, and a shell surrounding said pre-heating element in spaced relation thereto and embodying a bottom pan for receiving liquid fuel discharged out of said ports for ignition to heat said pre-heating element and thereby convert liquid fuel therein into gas to issue out of said ports for ignition by the ignited fuel in said pan, said shell being provided with air inlet slots for admitting air into the same to mix with such gas, and having an outlet slot for flame, and a baffle embodied in said shell opposite said ports for causing gas to rebound and spread around said pre-heating element.

2. A burner for use with a tubular casing forming a combustion chamber, said burner comprising a cylindrical hollow fuel pre-heating element adapted to extend endwise in said casing diametrically thereof and provided with fuel discharger ports therein adapted to discharge toward one end of said casing, a liquid fuel feed line to feed liquid fuel into said pre-heating element, a shell surrounding said pre-heating element in spaced relation thereto and embodying a bottom pan for receiving liquid fuel discharged out of said ports for ignition to heat said pre-heating element and thereby convert liquid fuel therein into gas to issue out of said ports for ignition by the ignited fuel in said pan, said shell being provided with air inlet slots for admitting air into the same to mix with such gas, and having an outlet slot for flame, and a baffle embodied in said shell opposite said ports for causing gas to rebound and spread around said pre-heating element, said shell being suspended by said fuel feed line in spaced relation to said pre-heating element.

GEORGE W. WARGO.
